(57) CLAIM

The ornamental design for lacrosse head, as shown and described.

DESCRIPTION

FIG. 1 is a perspective view of the lacrosse head embodying the new design;

FIG. 2 is an enlarged, perspective view thereof;

FIG. 3 is a side view thereof; and,

FIG. 4 is a top view thereof.

FIGS. 1–4 show features of an lacrosse head in phantom lines. These features are shown for environmental purposes and do not form any part of the claimed design. Further, the phantom lines immediately adjacent the solid-line portions of the design form the boundary of the design, with the phantom lines forming no part of the claimed design.
